UNITED STATES PATENT OFFICE.

HARRY WHITTAKER, OF METHUEN, MASSACHUSETTS.

NAPPING ROLLS.

Application filed January 21, 1929. Serial No. 334,047.

This invention has for its object the provision of means where bowing of the rolls in a napping machine will be prevented. At the present time the most general construction of napping rolls is a cylinder or thin tube which is mounted rotatably at its ends in heads which are, in turn, rotatable about a common axis. In order to obtain the desired results, the heads are rotated at high speed and the rolls are also rotated at high speed and in many machines adjacent rolls rotate in opposite directions. The surfaces of the rolls are covered with card clothing which runs in contact with the cloth or other material upon which a nap is to be raised and by contact with the surface of the cloth lifts the fibers or hairs of the same and produces the desired felted or napped surface. The cloth or other material is caused to travel around the series of rolls at the same time that the rolls are rotated in contact with the cloth and caused to travel in an orbital path. Owing to the high speed at which the heads travel, centrifugal action occurs and the central portions of the rolls spring outwardly with respect to their end portions so that an uneven contact with the material ensues and an uneven nap is produced. The bowing and consequent imperfect work varies according to the weight and size of the rolls but is present in an appreciable degree in all rolls. The present invention, therefore, aims to provide a structure which will permit the continued use of rolls formed of thin tubing so that the weight will be minimized and the power necessary to drive the rolls will not be excessive, while at the same time the rolls will be held in a true cylindrical formation with their walls concentric throughout with their axes and, therefore, maintain an even contact with the cloth or other material through the entire width of the latter. An embodiment of the invention is illustrated in the accompanying drawing and will be herein-after fully set forth.

In the drawing:

Figure 1 is a perspective view of a napping machine,
Fig. 2 is an enlarged longitudinal section through one of the napping rolls, and

Fig. 3 is a section on the line 3-3 of Fig. 2 further enlarged.

In the drawing, the reference numeral 1 indicates one of the heads and the reference numerals 2 indicate napping rollers mounted

in and carried by the heads so as to rotate therewith in the usual manner. In the construction and arrangement now generally employed, the heads 1 are constructed at 60 close intervals about their peripheries with bearing sleeves 3 in which are rotatably engaged trunnions at the ends of the napping rolls, and these bearing sleeves are constructed with oil holes 4 closed by plugs 5. 65 The heads 1 are rotated through gearing of known form and which need not be described in detail herein as it forms no part of the present invention and is well known to workers in this art. The napping rolls are provided with annular flanges 6 adjacent their ends or otherwise formed to provide drums or pulleys which are engaged by driving belts, indicated at 7 in Fig. 1, whereby the rolls will be rotated about their own axes 70 while being carried around the axes of the heads. In the most general arrangement, the belts 7 are provided at both ends of the napping drums and the two belts are arranged to engage and act upon alternate 75 rolls whereby the rolls will be driven alternately in the same direction but at different speeds. In carrying out the present invention, there is provided an axle 8 which is a solid rod and has its ends fitted tightly in 80 the bearing sleeves 3. If desired, clamping screws may be substituted for the plugs 5 in order to insure a rigid mounting of the rod but ordinarily the rod will be fitted so tightly in the bearing sleeves that no rotation will occur. Adjacent the ends of the rod and at the center thereof in the illustrated arrangement, raceways 9 are secured thereon and at corresponding points within the tubular roll collars or reinforcing 85 bands secured, anti-friction rollers or balls 11 carried by an outer raceway 12 being provided between said collars and the raceways 9. While I have illustrated three sets of bearings and raceways, it will be understood that the number of the raceways and 90 bearings may vary according to the length of the roll but the bearings should be equidistantly spaced and they constitute reinforcements to strengthen the roll and maintain the concentric relation of the same to the rod 8 throughout the length of the roll and at all times during operation.

The napping drum equipped with rolls embodying my invention is operated in precisely the same manner as napping drums are now operated and the rolls move in con-

tact with the cloth or other material in the same manner that the rolls now operate to produce a nap. Inasmuch, however, as the rod 8 is solid and rigid and is secured non-rotatably at its ends, it does not rotate in the bearing sleeves and is simply carried around by the drum heads in an inert manner. The rolls, however, will separately rotate about their respective axle rods and inasmuch as they are reinforced by the anti-friction bearings and mountings, they will be held against bowing notwithstanding that the drum heads may be driven at a very high speed. The tendency to bow under centrifugal action is effectually resisted by the several bearings which constitute reinforcements for the rolls without adding perceptibly to the weight of rolls now ordinarily employed. Inasmuch as the tendency of the rolls to bow is overcome, an even nap is produced upon the material and a higher grade product is obtained than has heretofore been possible with the same speed of operation. The arrangement does not necessitate any reconstruction of the drum heads nor any rearrangement of the operating gearing, but the invention may be applied to existing napping machines as well as embodied in machines to be hereafter built. The collars 10 and the

raceways may be secured in place in any convenient manner, as by shrinking, welding or otherwise. 30

Having thus described the invention, I claim:

1. A planetary napping machine comprising revoluble heads, a rigid axle rod extending the full distance between the heads and mounted stationarily at its ends in the heads, a tubular roll disposed concentrically about the rod between the heads, and rotatable reinforcements fitted between the rod and the roll at the ends thereof and intermediate the ends whereby bowing of the roll will be resisted. 35

2. A planetary napping machine comprising revoluble heads, a rigid axle rod extending the full distance between the heads, means for securing the rod at its ends in the heads whereby it will be non-rotatably held, a tubular shell disposed concentrically about the rod between the heads, and anti-friction bearings disposed equi-distantly within the shell and between the shell and the axle rod to prevent bowing of the shell and maintain the concentric relation of the same to the 40 rod. 50

In testimony whereof I affix my signature.
HARRY WHITTAKER. 55
